TABLET DISPENSER

Donald W. McTaggart, Agincourt, Ontario, Canada, assignor to Mead Johnson & Company, a corporation of Indiana
Continuation of application Ser. No. 524,120, Feb. 1, 1966. This application May 12, 1967, Ser. No. 638,155
5 Claims. (Cl. 221—267)

This is a continuation of Ser. No. 524,120, filed Feb. 1, 1966, and now abandoned.

This invention relates to a tablet dispenser, and more particularly to a dispenser which is especially useful to the taking of tablets on a schedule which must be synchronized with the personal schedule of the user.

The present invention is primarily adapted for aiding the dispensing and taking of contraceptive medication by women on an irregular schedule which must be properly synchronized with the physiological menstrual cycle of the individual. The dispenser is useful for dispensing any substance in tablet form and the indicia provided permit its use with a substance which must be dispensed on a schedule. The description herein of the invention and its use is directed primarily to dispensing contraceptive medication.

The principal object of this invention is to provide a new and improved dispenser particularly adapted for dispensing tablets on a schedule.

Another object of this invention is to provide a dispenser which serves as a simple and helpful aid to an individual taking medication on an irregular schedule.

A further object of this invention is to provide a dispenser having a novel construction that is easily contained in a case indistinguishable from a lady's tube of lipstick and adapted to be carried among the personal effects of a lady in a purse, or the like, without disclosing matters which are personal to the individual.

Still another object of this invention is to provide a tablet dispenser of the character described which is easily manipulatable and easily synchronized by the user with the personal schedule of the individual.

Other objects and advantages of the invention will become apparent from the following detailed description taken in connection with the accompanying drawings, in which:

FIGURE 1 is an elevation view of a dispenser embodying the invention and encased within a cover simulating a tube of lipstick;

FIGURE 2 is an enlarged elevation view of the dispenser with the cover removed;

FIGURE 3 is a sectional view, taken generally along the line 3—3 of FIGURE 2;

FIGURE 4 is a top plan view of the dispenser as shown in FIGURE 2, with the plunger element removed;

FIGURE 5 is a top plan view of the plunger element;

FIGURE 6 is a side elevation view of the plunger element of FIGURE 5; and

FIGURE 7 is a rear elevation view on a reduced scale of the dispenser of FIGURE 2.

The invention is illustrated herein as embodied in an elongated tablet dispenser incorporated in a construction indistinguishable from a lady's tube of lipstick, as illustrated in FIGURE 1. A tablet holder generally designated 10 (FIGURE 2) is adapted for insertion into a decorative removable tubular cover 12 (FIGURE 1). Thus, the dispenser comprises a novel construction which is adapted to be carried among the personal effects of a lady in a purse, or the like, without revealing matters which are personal to the individual. The holder 10 includes an enlarged base 14 having a plurality of peripheral lugs 14a about which the lower portion of the cover 12 is securely

2

positioned to space the cover from the balance of the holder. The lower end of the holder 10 has a sloped flange 16 with an upper surface 16a against which the lower edge of the cover 12 abuts.

5 The holder 10 is comprised of an elongate tubular member 18 which contains a plurality of tablets T stacked therein. The tubular member has an open end 20 (FIGURE 4) which defines a mouth for dispensing the tablets one at a time from the end of the stacked adjacent the mouth. The mouth may be formed slightly smaller than the diameter of a tablet to prevent the tablets from falling therethrough, or the mouth may include several protrusions 28 to prevent accidental dispensing of a tablet. The tubular member 18 includes a marginal stiffening flange 15 22 about the mouth. An elongate slot, generally designated 24, extends substantially the entire length of the tubular member 18 and extends into the mouth 20 to provide flexibility at the mouth to permit tablets to be forced therethrough. The slot 24 also provides a path for the 20 movement of the plunger head (hereinafter described).

A plurality of teeth 25a are disposed along at least one side of the slot 24 and extend transversely into the slot. The teeth are spaced in accordance with the thickness of the tablets T stacked in the tubular member 18 whereby a 25 gap 25b between adjacent teeth registers with a single tablet contained in the tubular member.

An actuating member in the form of a plunger element 26 is positioned in the tubular member at the end of the stack of tablets remote from the mouth of the tubular 30 member. The plunger is the means through which manual force is transmitted to the stack of tablets to dispense them one at a time through the mouth 20. The plunger 26 includes a boss 26a extending into slot 24 and a pointer head 26b at the outer end of boss 26a. The boss 26a is of 35 such a size as to fit snugly in the gaps 25b between adjacent teeth 25a in slot 24. Thus, the application of force in the direction of arrow A (FIGURE 2) on the plunger head 26b urges the plunger 26 against the remote end of the stack of tablets. Sufficient force will cause the boss to 40 "snap" past a tooth 25a, thereby "popping" a single tablet from the open mouth 20 of the dispenser for every tooth passed by the boss.

The tablet holder 10 and plunger 26 may easily be molded of lightweight plastic material and the cover 12 45 may be formed of a metallic material thereby resembling a tube of lipstick or the like.

The indicia and markings embodied in the dispenser shown in the drawings are employed to adapt the holder of this invention for use by women in the taking of a contraceptive medication where dosage starts several days 50 following the first day of the menstrual period. Obviously, the indicia may be much simpler for the systematic dispensing of tablets where the delayed starting of the use is not involved.

55 In the embodiment illustrated, a plurality of numerical indicia, generally designated I, are disposed along one side of the slot 24. The indicia shown include the numbers 5 through 25 inclusive intended to indicate the corresponding days in the menstrual cycle. The first tablet is taken 60 on the fifth day of the menstrual cycle and another is taken on each successive day. The pointer-like plunger head 26b moves with the plunger as the stack of pills are depleted and points to the particular numerical day of the menstrual cycle as the tablets are taken on a daily 65 schedule.

In order to eliminate the necessity of keeping an independent record of the particular day when one's menstrual cycle started and what day of the week corresponds to the numbers 5 through 25 described above, a plurality of 70 marking positions, generally designated M, are disposed on the opposite side of slot 24 in registry with the numeri-

cal indicia I. These positions are formed by a frosted or roughened surface area on the plastic tubular member, divided by 18, a plurality of dark lines 28, opposite teeth 25a, into an area for each tablet. The marking positions, being frosted, are adapted to receive writing such as the first letter of the days of the week, as illustrated in the drawings.

An individual may write the first letter of the day of the week which corresponds to the fifth day of her menstrual cycle opposite the numerical indicia 5, etc., successively through number 25. Thus, a schedule of taking pills can easily be synchronized with the personal schedule of the user by simply placing appropriate marks in the marking positions. The day of the week marking positions, the gaps 25b between teeth 25a and the numerical indicia I are in transverse alignment. Tips 30 on each side of the plunger head, FIGURE 2, point to the indicia and the marking positions to provide a time reference indicator which facilitates rapid visual registration of the numerical indicia and the day of the week markings in relation to the number of tablets remaining in the dispenser and thus the particular time in the menstrual cycle.

The tablet dispenser of this invention is especially useful when employed with a systematic or sequential system of medication. For instance, a known sequential system of contraceptive medication requires tablets containing an estrogenic agent be taken from day 5 through day 20 of the menstrual cycle and a tablet containing a progestational-estrogenic agent be taken from day 21 through day 25 of the menstrual cycle. The two types of tablets are preferably of different colors to permit easy identification. Since the dispenser of this invention necessitates the dispensing of tablets one at a time from one end of a "planned" stack of tablets, the proper sequence of taking tablets in a systematic or sequential system is insured.

A grated window, generally designated W in FIGURE 7, is disposed diametrically opposite the slot 24 in the tubular member 18 and performs two functions in the embodiment of this invention, as illustrated in the drawings. The window provides support openings through which core pins may be inserted to stabilize the inner core of the mold during the molding of the plastic tubular member. Without stabilizing core pins, it is difficult to mold a concentric tubular member and a portion of the molten plastic material would bridge over the slot 24. Secondly, the window is positioned so that only one of the differently colored progestational-estrogenic tablets is exposed when the dispenser is completely filled with its desired number of tablets whereby a rapid visual inspection insures that a correct number of each type of tablet is contained in the tubular member. Each layer of tablets lines up with each of the horizontal grill patterns in the window.

While this invention is susceptible of embodiment in many different forms, there is shown in the drawings and will herein be described in detail an embodiment of the invention with the understanding that the present disclosure is to be considered as an exemplification of the principles of the invention and is not intended to limit the invention to the embodiment illustrated. The scope of the invention will be pointed out in the appended claims.

I claim:

1. A tablet dispenser, comprising: an elongate tubular member containing a plurality of tablets stacked in one

end thereof, said one end being open to define a mouth for dispensing tablets from the stack, the periphery of the mouth being slightly smaller than a tablet to hold tablets in the tubular member against unintended dispensation, 5 said tubular member including a slot extending the length of a full stack of tablets and through the open end of said tubular member to provide flexibility in the mouth for temporarily enlarging the mouth responsive to the application of force on the tablets in the direction of the mouth to affect sequential dispensation of tablets out of said mouth, said slot having a plurality of teeth along one side thereof and extending into the slot, adjacent teeth being spaced a distance equal to the thickness of a tablet, and a plunger element in said tubular member at the end 10 of the stack of tablets remote from said mouth, said plunger element being adapted to transmit force to the remote end of the stack of tablets to dispense tablets from the stack through said mouth, said plunger element including a boss extending into said slot, said boss fitting snugly in a gap between adjacent teeth in said slot whereby on forcing said plunger against the stack of tablets said boss snaps past said teeth, popping a single tablet from the dispenser for every tooth passed by said boss.

2. The tablet dispenser of claim 1 including numerical indicia on said tubular member along said slot, said indicia being correlated with the length of the slot, the teeth extending into said slot, the thickness of individual tablets and sequential units of time within a cycle to relate the tablets remaining in the dispenser to a portion of time 20 remaining in the cycle to verify proper usage of the tablets.

3. The tablet dispenser of claim 1 including a window in said tubular member remote from said slot, a portion of the window positioned relative to the top of the stack 25 of tablets when the dispenser is filled with its desired number of tablets to provide a rapid visual inspection means for determining that the correct number of tablets is contained in the tubular member.

4. The tablet dispenser of claim 2 wherein said tubular member has a plurality of discrete marking positions on one side of the slot, each being correlated with the tablets, the numerical indicia along the slot and the teeth extending into said slot, for receiving markings by a user at the initiation of a critical portion of a cycle to permit 40 the dispensing of tablets on a schedule by placing opposite each tablet the appropriate marking corresponding to the desired schedule of usage thereby synchronizing the tablet dispenser with the personal schedule of the user.

5. The tablet dispenser of claim 4 wherein the marking positions are located on said tubular member on the side of said slot opposite the teeth that extend into the slot and wherein the plunger has a pointer portion directed toward the marking positions and the indicia to facilitate rapid visual registration of the marking positions in relation to the number of tablets remaining in the dispenser as the plunger bears against the remote end of the stack of tablets.
